UNITED STATES PATENT OFFICE.

WILLARD PRESCOTT HAWLEY, OF PORTLAND, OREGON.

DISPENSING-BOX.

1,258,003.

Specification of Letters Patent.

Patented Mar. 5, 1918.

Application filed September 8, 1915. Serial No. 49,447.

To all whom it may concern:

Be it known that I, WILLARD PRESCOTT HAWLEY, of Portland, in the county of Multnomah and in the State of Oregon, have invented a certain new and useful Improvement in Dispensing-Boxes, and I do hereby declare that the following is a full, clear, and exact description thereof.

My invention relates to boxes adapted to dispense folded sheets of material of all kinds, but it is especially adapted for use in connection with folded paper sheets such, for example as, paper towels, etc., and particularly such sheets when in the form of packs of interfolded sheets.

The object of my invention is to provide a construction of this character, in which the sheets may be readily removed from the container. A further object of my invention is to provide such a construction in which the free ends of the sheets, being removed from the container, will not become wrapped around nor entangled in the parts used for reducing friction.

While my invention is capable of embodiment in many different forms, for the purpose of illustration, I have shown only one form thereof in the accompanying drawings, in which,

Figure 1 is a front elevation of an apparatus made in accordance with my invention; and

Fig. 2 is a transverse vertical section of the same.

In the drawings I have shown a box 1 made of metal or any other suitable material, having a door 2 at the front thereof carried by a pair of hinges 3 at the bottom of the door and adapted to be releasably held in place by a catch 4 at the top of the door engaging with a projection 5 upon the container 1, said catch having a pin 6 projecting

outwardly through the door so as to enable the catch to be operated when desired. At the bottom of the box there is an outlet opening 7, at either side of which there is located a tube 8 of metal, or any other suitable material, a section of which has been removed.

In the tubes 8, shown in the drawings, about one-quarter of each of the tubes has been removed in this manner. These tubes 8 having heads, are journaled on rods 8^a, which

rods are held in place by straps 9^a on the bottom of the box 1, and the tubes are continually forced upwardly by coil springs 10, located in the interior of the tubes and having their upper ends 11 soldered or fastened in any other desired manner to the bottom of the box, and their lower ends 12 rest against the lower free edges of the sectional tubes 8. A pack of folded paper sheets 13, as for example, paper towels, is adapted to be contained within the box 1, the same being inserted by opening the door 2, and in such a manner that the lowermost sheet has its free edge 14 projecting through the opening 7 in the bottom of the box. In order to remove one of the towels, it is merely necessary to pull upon the free edge 14 of the lowermost towel in the box. While the towel is thus being pulled out of the box, the tube 8, which is adjacent to the part of the towel being moved rotates a quarter of a revolution during the removal of the towel, and as soon as the same has been removed, said tube flies back under the influence of the spring 10, located in the same, thus reducing the friction due to the removal of the towel from the box 1. This results in the withdrawal of the lowermost towel from the box, and at the same time, the withdrawal of the free edge of the next succeeding towel in the pack 13 from the box, so that it projects through the opening 7. When the next towel is being removed from the box 1, in a similar manner, the other tube 8 is rotated as already described in regard to the other first mentioned tube, so as to reduce the friction incident to the removal of the towel from the box. The towels are thus removed from the box, one after another, and the construction of the parts provided for reducing friction is such as to obviate the possibility of the free ends of the towels becoming entangled therewith or drawn into the box due to the rotation of the said parts.

While I have described my invention above in detail, I wish it to be understood that many changes may be made therein without departing from the spirit of my invention.

I claim:

1. A box constructed so as to dispense paper sheets, and a friction device thereon, comprising an oscillating tube, having a circumferential section thereof removed.

105

110

2. A box constructed so as to dispense paper sheets, and a friction device thereon, comprising a spring-pressed oscillating cylinder moved in one direction by the sheets 5 as they are withdrawn, and in the other by the spring.
3. A box constructed so as to dispense paper sheets, and a friction device thereon, comprising a spring-pressed oscillating tube, 10 having a circumferential section thereof removed to receive the edge of the box.
4. A box constructed so as to dispense interfolded paper sheets, having an opening, and a friction absorbing device located at 15 each side of the said opening, comprising a member oscillating about its own axis.
5. A box constructed so as to dispense interfolded paper sheets, having an opening, and a friction device located at each side 20 of the said opening, comprising an oscillating cylinder moved in one direction by the sheets as they are withdrawn, and having means acting upon it to move in the opposite direction.
- 25 6. A box constructed so as to dispense interfolded paper sheets, having an opening, and a friction device located at each side of the opening, comprising an oscillating tube, having a circumferential section there- 30 of removed to receive the edge of the box.
7. A box constructed so as to dispense interfolded paper sheets, having an opening, and a friction absorbing device located at each side of the opening, comprising a spring-pressed oscillating member moved in 35
- one direction by the sheets as they are withdrawn, and in the other by the spring.
8. A box constructed so as to dispense interfolded paper sheets, having an opening, and a friction device located at each side 40 of the opening, comprising a spring-pressed oscillating cylinder moved in one direction by the sheets as they are withdrawn, and in the other by the spring.
9. A box constructed so as to dispense interfolded paper sheets, having an opening, and a friction device located at each side 45 of the opening, comprising a spring-pressed oscillating tube, having a circumferential section thereof removed to receive the edge 50 of the box.
10. A box constructed so as to dispense paper sheets, and a friction device thereon, comprising a cylinder rotated about its own axis as the sheets are withdrawn, and having means for returning it to its original 55 position.
11. A box having a paper sheet dispensing opening, a friction absorbing cylinder rotatably mounted adjacent said opening, 60 and means for acting upon said cylinder to rotate it oppositely to the rotation imparted by the withdrawal of the sheets.

In testimony that I claim the foregoing I have hereunto set my hand.

WILLARD PRESCOTT HAWLEY.
